UNITED STATES PATENT OFFICE.

EDWARD J. GULICK AND MORRIS V. HAWKINS, OF ELKHART, INDIANA, ASSIGNEES TO
C. G. CONN, LTD., OF ELKHART, INDIANA, A CORPORATION OF INDIANA.

MACHINE FOR FORMING SOCKETS ON MUSICAL INSTRUMENTS.

Application filed October 19, 1922. Serial No. 595,672.

To all whom it may concern:

Be it known that we, EDWARD J. GULICK and MORRIS V. HAWKINS, citizens of the United States, and residents of the city of 5 Elkhart, county of Elkhart, Indiana, have invented new and useful Improvements in Machines for Forming Sockets on Musical Instruments, of which the following is a specification.

10 This invention relates to improvements in the manufacture of musical instruments and particularly brass instruments, like saxophones.

15 It is an object of the invention to provide a method and a machine for producing on the bodies of brass instruments tubular projections or projecting sockets which in the finished instruments serve as valve seats.

20 It is an object of the invention to apply these sockets to the body of the instrument by producing them as an integral portion of the body.

25 It is furthermore an object of the invention to provide a method and a machine in which the production of the socket is effected by applying a pulling force at a predetermined point in the interior of the body outwardly thereof, so as to create protrusions at predetermined points of the body.

30 It is also an object of the invention to provide a method and a machine by means of which sockets of different diameters may readily be applied without necessitating alterations in the mechanism of the machine.

35 The invention also contemplates to provide means for applying these sockets in different planes intersecting the body of the instrument radially.

40 Another object of the invention is to securely lock the saxophone body during the treatment in the machine against rotation about its axis and to also hold it against longitudinal displacement in order to effect the production of a true cylindrical socket.

45 By means of the machine described.

The invention also has the object of providing a method whereby the inner surface as well as the outer surface of the protruding socket produced is thoroughly smoothed during the production of the same, avoiding thereby all burs or other projections in the walls of the socket.

The invention also has the object of facil-

tating the rapid location and mounting or dismounting of the saxophone body on a 55 support which forms a part of the machine.

With these and numerous other objects in view the method is described in the following specification to be carried out by means of a machine which is also described by way 60 of example, the novel features being pointed out in the appended claims.

In the drawings:

Figure 1 is a front elevation of the machine, certain parts being shown in section; 65

Fig. 2 is a detail elevation with parts shown in section, of the turret in its relation to the saxophone body in operative position of a socket;

Fig. 3 is a section on line 3—3 of Fig. 2; 70

Fig. 4 is a detail section of the adjusting mechanism for the turret, on line 4—4 of Fig. 2;

Fig. 5 is a portion of a section on line 5—5 of Fig. 1, showing the indexing mechanism; 75

Fig. 6 is a sectional view on line 6—6 of Fig. 5, certain parts being shown in elevation;

Fig. 7 is a portion of a section also on line 80 5—5, Fig. 1, showing a locking mechanism for retaining the instrument carriage in a predetermined position;

Fig. 8 is a sectional detail view through the index wheel locking mechanism; 85

Fig. 9 illustrates the shank for the pulling ball, partly in section and partly in elevation, and

Figs. 10, 11 and 12 are elevation, central section and top plan view respectively of the 90 pulling ball.

The body of a brass instrument and particularly the body of a saxophone usually comprises a more or less tapering hollow member of sheet metal. In order to modulate the sound, the finished instrument is provided with valves which are not shown in the drawing and which are to be controlled by the player. The method and machine described in the following aim at the 95 production of small protuberances or sockets extending from the body of the instrument outwardly and serving in the finished instrument as seats for the manually controlled valves. In order to produce these 105 sockets the tapering body S is therefore

provided with holes *b* which are considerably smaller in diameter than the sockets to be formed by the enlargement of these holes and by the production of cylindrical flanges rising from the saxophone body.

The method, therefore, may be said to consist essentially in drilling a hole in a saxophone body and then enlarging said hole by pulling the material adjacent the edges of the hole outward and shaping said pulled portion of the material into truly cylindrical form. The method, concisely stated, includes the steps of placing a pulling tool in the interior of the saxophone body and then forcibly withdrawing said tool radially outward through the previously provided opening, thereby enlarging said opening and creating flanges which surround the enlarged opening. These steps are combined with the steps for confining the size of the flange or diameter of the socket produced and with the steps of smoothening the inner surface of the socket during the production thereof.

While various machines may possibly be utilized for carrying out the method, a preferred embodiment of a machine for performing the method is described in the following and also forms a part of the present invention.

The frame of the machine comprises a standard 1 which supports a longitudinal bed or table 2 of channel shaped cross-section, Fig. 5.

The bed supports a movable carriage 6 having on its under face a rack bar 7, Fig. 5, in permanent engagement with a pinion 8 which is mounted on a shaft 9 journaled at a suitable place in the walls of the bed. The spindle 9 is equipped with a hand wheel 10 whereby upon rotation of this hand wheel and the pinion 8, the carriage 6 may be adjusted longitudinally of the bed.

For the purpose of guiding the carriage 6 in this movement, the bed is provided on the front wall with an undercut longitudinal projection 11, while the opposite wall has a straight shoulder 12 and supports a jib or bar 13 presenting an undercut surface opposite to that of the shoulder 11. The carriage 6 engages these undercut surfaces by means of a downward projecting extension having suitably beveled edges. The necessary pressure may be maintained through the adjustment of screws 14 which impinge against the back of the jib 13.

The carriage 6 carries near one end an enlargement through which extends a transverse pin 15. On this pin is pivotally mounted the rear end of the support 16 which extends longitudinally of the machine and which is preferably constructed as shown in Fig. 5 of a channel shaped cross-section opening downward, this support also having on its upper surface an undercut pro-

jection which may extend substantially over the entire length of the support, as illustrated in Fig. 1. It will be obvious, therefore, that upon longitudinal displacement of the carriage 6, the support 16 also will be displaced longitudinally, while transverse adjustment may be effected through the transverse adjustment of the bed described. Furthermore, the angular position of the support with respect to the carriage and bed may be altered owing to the pivotal connection of the carriage 6 with the support 16.

The support 16 serves for receiving spaced bearing elements by means of which a mandrel is rotatably carried and by means of which this angular relation of the mandrel relatively to the bed or carriage 6 may be altered, depending upon the requirements of the case. One end bearing, as shown in Figs. 1 and 6, comprises a tubular head 17 on an integral stem 18. This bearing has a swivel connection with the support 16 and for this purpose a collar 19 is secured on the support 16 above the pivot 15 of the same. The stem 18 carries fixed thereto at its lower end a plate 21 of slightly larger diameter so as to be in marginal engagement with an overlying portion of the collar 19 and to be rotatable within the same. From this construction it is apparent that the bearing 17 may be rotated in a plane in which the surface of the support 16 is disposed.

Within the bearing 17 is rotatably mounted a bushing 24, Fig. 6, which is keyed to one end of the mandrel 25. The other end of this bushing is fixedly connected with a hand or indexing wheel 26. Upon rotation of the hand wheel, therefore, the mandrel 25 may be rotated about its axis. Longitudinal displacement of the bushing 24 relatively to mandrel or bearing, however, is prevented owing to the provision of a flange 22 and a threaded collar 20 which engage the bearing, while the nut 23 on the extension of the mandrel prevents axial displacement of the indexing wheel.

The tapering mandrel 25 conforming with the interior surface of the saxophone body *S* is held at the opposite end in a tail stock 28 similar to the tail stock of an ordinary lathe. This end bearing 28 is adjustably secured to the dovetail extension of the support 16, as shown in Fig. 1, and is provided with a spindle 27 having a pointed end which enters a suitable central socket in the mandrel 25. The spindle 27 has at its rear end a tapped bore into which the screw 29 extends. A displacement of the spindle may be effected by rotation of the nut 30, which is constructed as a hand wheel.

After the body *S* has been placed on the mandrel 25, it is held against rotation or axial displacement thereon in any suitable way, as for instance, by a locking screw 31,

Fig. 1, which enters through an opening of the body S into a tapped bore of the mandrel, Fig. 1.

As the valves on instruments of this kind are not all arranged in the same axial plane of the body, it is necessary to rotate the mandrel and the body thereon, to bring individual sockets or a series of sockets simultaneously into the plane of operation of the tool. The wheel 26 is provided with indexing sockets 26' on that face which is directed towards the bearing 17. A tubular lug 32 is united with the bearing 17 and contains a plunger 33 controlled by the spring 34, Fig. 8, which acts on a collar of the plunger and on a fixed closing member 35 of the sleeve 32. The reduced end of the plunger 33 is adapted to enter one of several sockets 26' in the rear face of the hand wheel 26, to lock thereby the hand wheel and the mandrel against rotation about their axis. The withdrawal of the plunger 33 from the socket into which it has been inserted is effected by rotation of a handle 37 fixed to the plunger 33 on a collar which is provided with a cam surface 39. This cam surface cooperates with a companion cam surface 40 on the closing member 35' of the lug 32. Upon rotation of the handle 37 in one direction, the cam 39 will affect an axial withdrawal of the plunger, against the tension of spring 34, while upon rotation of the handle in the opposite direction, the spring 34 will force the plunger into a socket 26' if the wheel and body S have been turned to bring one of these sockets into opposition with the plunger.

A standard 36, which is connected with the bed 1 of the machine similar to the ordinary standards of drill presses, is provided with aligned bearings through which the tool spindle 41 rotatably extends and in which this spindle also is slidably so as to be lowered towards the work or raised to withdraw from the work,—a construction which is well known from ordinary drill presses. The spindle 41 passes slidably through a bevel gear 42 which is held against axial displacement. This bevel gear is driven through a companion gear 43 which may be operated from any source of power, (not shown).

The mechanism for manually raising and lowering the spindle 41 is indicated by a hand wheel 44 at the side of the standard and combined with a pinion 45 engaging a rack 46 which is held against rotation in the machine; but which is slidable together with the spindle 41.

The lower end of the spindle carries a chuck 47 to receive the shank of a tool which will be described below. This tool is properly positioned in relation to the opening in the body S by means of a bushing or

the like. A plurality of these bushings are collectively mounted in a carrier or turret 38.

This turret comprises a bottom plate 48 and a flaring flange 49; which is provided with a plurality of openings of different diameter. These openings, as will be seen in Figs. 2 and 3, are equipped with the bushings 50, each preferably having a reduced portion 51 which has a driving fit in the respective opening of the turret, and a reinforced outer portion 52, the free edge of which is curved, Fig. 3, so as to straddle the conical portion of the body S adjacent the opening to be protruded. This turret is rotatably adjustable and its axis is at an angle to the axis of the spindle, the flange 49 being in such angular relation to the turret axis that the portion of the flange which is in operative position, Fig. 3, presents a bushing with its axis vertically disposed. By reference to Fig. 1, it will be seen that nine of these guiding bushings 50 are provided in the turret, and these bushings may have all different diameters or several of them may have different diameters to produce different sized sockets.

For the purpose of adjusting the turret selectively to any of the numerous operative positions, a bracket 53 comprising a split collar surrounds the standards 36 which rises from the base of the machine, Fig. 1. The bracket 53 is held in adjusted position through clamping screws which draw the split parts together, Fig. 3. The front face of this adjustable collar is flattened and provided with dovetailed guide-ways 54, in which the turret support 54 is vertically slidable and on this support the turret is rotatably mounted in that angular relation to the axis of the standard which has just been described. The collar 53 is provided near the upper end with a rack bar 55 and this rack bar is engaged by a pinion 56 carried on a horizontal shaft 57 supported in a laterally extended bearing 58, Fig. 2, which forms a part of the turret support 54. This support, therefore, may be vertically adjusted relatively to the standard 36 by rotation of the pinion 56, and the rotation of this pinion 56 and the spindle 57 is effected manually by means of a worm transmission gear, shown in Fig. 4. The extended bearing 58 for the spindle 57 terminates in a housing 59 in which the spindle 57 is equipped with a worm gear 60 in mesh with a worm 61 at the lower end of a shaft 62 which is supported in the housing 59 and in bearings of a conical extension 63. The projecting end of the shaft 62 carries fixedly the hand wheel 64, whereby through the rotation of the hand wheel and worm 61, the worm gear 60, the spindle 57 and the pinion 56 are turned, the pinion then also being vertically displaced along the rack bar 55.

By this means the entire turret support 54 is raised or lowered relatively to the saxophone body and to the parts of the machine.

The turret is rotatably carried on the support by a pin or bolt 65 extending through the support. The inner end of this pin 65 has a relatively large flat head 66 which fits into a recess 67 on the lower face of the bottom 48 of the turret. Holding screws 68 of which four are illustrated in Figs. 2 and 3, are threaded into the head 66 and thereby secure the turret to its pivot 65. A nut 69 is mounted on the opposite projecting end of the pivot pin.

Locking devices maintain the turret in any one of several predetermined operative positions, and for this purpose, sockets 70 in bottom part 48 are each adapted to receive the conical reduced portion of a spring controlled plunger 71, which is slidably mounted in a bore 72 of the turret support. This plunger projects through a closing member 73 of the bore 72 and carries on its projecting end a head with a lateral enlargement 74. In a lug 75 secured to the turret support a dog 76 is pivoted at 75' whose head 77 is adapted to engage the lateral enlargement 74. The tail 78 of dog 76 carries an adjustable stop screw 79, the head of which in operative position of the turret, as shown in Fig. 3, contacts a stop 80 fixed in the main bracket 53 or to some other point on the machine, and which projects through a slot 81 of the turret support.

When through rotation of the hand wheel 64, the turret is raised from the position shown in Fig. 3, after the completion of a socket, the fixed stop 80 will induce a swinging movement of the dog 76 whereby the locking element 71 is withdrawn from the pertaining socket 70. The turret, however, is still retained in its former relation to the support by an auxiliary locking device consisting of a spring pressed ball 82 which is located in a bore 83 of the support and which is adapted to enter auxiliary sockets 84 in the bottom 48. This auxiliary locking device, is however, a yielding device, and the operator upon using suitable force may rotate the turret, overcoming the tension of the spring which acts on the ball 82 and may rotatably adjust the turret to a new position, in which another socket 84 will be in opposition to the ball 82 so as to be retained thereby. When this rotary adjustment is completed the operator may lower the turret support with the turret to seat the lower edge of another bushing 50 over the respective opening in the saxophone body, and during this lowering movement the locking device formed by the spring controlled plunger 71 will automatically enter into action to hold the turret against accidental displacement.

The bed is adjustable back and forth by means of the gear and rack connection illus-

trated, or in some other way. A bearing lug 3 projecting from the standard carries a spindle 4, the lower projecting end of which has the crank handle 5. The pinion 4' at the upper end meshes with a rack 2' associated with the bed whereby upon rotation of the crank the bed will be moved on a plate 1' provided with undercut grinding ledges.

In order to produce truly cylindrical flanges, the saxophone body S must be adjusted to place that line on which an axial series of sockets are arranged in true horizontal position, or in other words, instead of having the axis of the mandrel and saxophone body horizontally on the machine, this body and the mandrel must be inclined to produce a horizontal position of that line on which a plane defined by the axis of body S and by the axis of the socket intersects the body.

For this purpose, the front end of the support 16 carries an adjusting screw 88, which with its lower end impinges on a portion of the bed 6, whereby through rotation of a nut 89, mounted on the free end of the support 16, this end will be raised and lowered to swing the entire support on the pivot 15 which forms the connection between the carriage 6 and the support. After the adjustment has been accomplished and the axis of the socket to be produced has been placed in truly vertical position, a prop 90' of suitable height may be inserted between the carriage 6 and the support 16, and this adjustment including the insertion of the prop 90' may be maintained as long as saxophone bodies of equal tapering relation have to be treated in the machine.

A gauging device may be associated with the carriage 6 and the bed 2. The carriage 6, therefore, is provided with a gauge bar 90 detachably fixed to the front surface of the same and showing a plurality of sockets 91 into which a locking element may enter. The locking device, Fig. 7, is constituted by a bracket 92 fixed at a certain point of the bed 2 and having in its tubular head a locking plunger 93 controlled by a spring 94. The bore is closed by plugs 95, of which one is equipped with a cam surface 96. The projecting end of the plunger 93 carries fixed thereto a collar 97 having a companion cam surface 98 and a handle 99. Upon rotation of this handle in one direction the plunger naturally will be withdrawn from the position shown in Fig. 7, overcoming the action of the spring 94. The carriage can then be longitudinally displaced by means of the hand wheel 10, and when the plunger is during this displacement released to the action of spring 94, it will be forcibly advanced, as soon as the next socket 91 comes in opposition with the plunger, whereby the carriage is locked against further displacement. The sockets 91 on the bar 90 are spaced so as to

agree with the axial distances between the sockets to be produced on the saxophone body. Owing to this arrangement an automatic retention of the saxophone body 5 against axial displacement in operative position is obtainable.

The tool, as illustrated in Figs. 9 to 12, comprises a head or ball 100 of substantially the shape of a portion of a spherical body. It is preferably provided with symmetrically arranged pockets or recesses 101 between which ribs 102 of approximately spherical contour are left. The ball 100 has a short cylindrical extension 103, and centrally above this cylindrical extension a tapped bore 104 extends into the body of the ball.

One of these heads 100 is inserted into each recess 106 on the mandrel which forms the support of the instrument body, the recess being in alignment with the hole of the instrument body to permit the introduction of a withdrawing element 107. The upper end of this element is seated in a shank 108 and is held locked in the adjusted position by means of a nut 109. The free end of the withdrawing element or stem 107 is threaded to engage the tapped bore 104 of the head 100. The shank is gripped by the chuck 47, as shown in Fig 1, and any desirable chuck may be used for this purpose.

The method of producing flanged sockets on the saxophone body, therefore, comprises the steps of drilling holes into the saxophone body by means which are very well known, and then expanding these holes from the interior of the body outwardly. This method also includes the steps of shaping the flanges which are produced by this outward expansion and particularly to limit the outer diameter of the flanges, this limitation being due to the positioning of the lower ends of the bushings in the turret on the saxophone body.

The machine which may be utilized for carrying out the method just described operates in the embodiment illustrated, in the following way:

The saxophone body provided with perforations is placed on the mandrel and held against rotation thereon by means of the key 31, the hole of which may be closed subsequently if desired. Previous to the emplacement of the saxophone body on the mandrel, the openings in the mandrel were each provided with one of the balls 100 which are utilized later for enlarging and protruding those openings which have been drilled into the saxophone body at the places where the valves or sockets are to be located. This mandrel with the saxophone body mounted thereon is then placed into the machine by rotating the bearing 17 about the vertical axis of the foot 18. After the extension on body support 25 has been inserted

through the bearing bushing 24 the hand wheel 26 is secured thereto, the location of this hand wheel being fixed, owing to the provision of a key which unites this hand wheel with the bearing bushing. The nut 23 then fastens this indexing wheel 26 and retains the entire assembly of parts in predetermined relation to each other.

The reduced end of the mandrel is secured in place in the tail bearing 28 by first withdrawing the spindle 27 and then advancing the same until the reduced point of the spindle enters the socket in the tapering end of the mandrel.

The gib 90 desired to be used for that particular type of saxophone or possibly only for a particular series of sockets, is then mounted on the carriage 6 and brought into suitable relation with the locking device 92 on the bed.

In its vertical plane the tapering mandrel is now adjusted to move the axis of the saxophone body from horizontal position and to bring that mantle line of the body on which the socket or sockets are to be located, into a truly horizontal plane. This is effected by suitable adjustment of the screw at the free end of the support 16 and in this adjustment the support is rocked about the supporting pivot 15 at the end of the carriage 6. It is obviously then that upon subsequent rotary adjustment of the mandrel about its axis there will be always a mantle line at the top of the body which is truly horizontal. A prop may then be inserted under the support 16 for relieving the adjusting screw from excessive strain.

Through rotation of the hand wheel 10 after withdrawal of the locking plunger 93, the carriage 6 is now displaced on the bed 2 until the selected socket hole *b* of the body is in alignment with the axis of the spindle 41. When this alignment is attained, the locking plunger 93 will be in opposition to a socket 91 on the bar 90 and when released to the action of the spring 94 it will automatically snap into said socket and lock the parts against further displacement.

This adjustment of the mandrel is followed by a selection of the bushing, for, depending upon the size of the socket to be produced, a certain bushing must be applied. The operator rotates the hand wheel 64 and thereby the worm transmission 61, 60, until, owing to the rotation of the pinion 56 the turret bracket 54 is raised. In this elevating movement of the turret bracket, the stop screw 79, prevented from following the movement of the bracket, will cause the dog 76 to withdraw the locking plunger 71 from its corresponding socket in the bottom of the turret. The operator now overcoming the auxiliary locking device 82 rotates the turret until the selected bushing is in opposition with the socket hole into which the

withdrawing element is to be inserted. When this adjustment has been completed (and the operator is aided in the adjustment by the automatic entry of the locking ball 82 into the socket 81), the operator rotates the hand wheel 64 in opposite direction and again lowers the turret bracket 54 during which movement the spring will now advance the plunger 71 into a corresponding socket 70 in the bottom of the bushing carrier. This lowering movement of the turret bracket 54 is continued until the selected bushing straddles that portion of the saxophone body which contains the socket hole 7 to be expanded.

The operator may now throw in a clutch or shift a belt, not shown, through which the drive is transmitted to the spindle 41. At the same time, he lowers by means of the hand wheel 44 this spindle into the socket hole 7 and owing to the rotation of the spindle and its downward movement, the threaded part of the element 107 will enter the tapped bore 104 of the ball 100, thereby causing a screw connection between these parts. If now the operator reverses the reciprocating movement of the spindle without interrupting its rotation, the ball firmly gripped by the withdrawing element will be drawn upwardly through the socket hole and will thereby expand the metal of the saxophone body, forcing it into engagement with the reinforced flange 52 of the bushing and imparting to the metal of the saxophone body a substantially cylindrical shape defined by the size of the head 100 and the size of the bushing with which it cooperates. After the socket has been completed, the operator may repeatedly raise and lower the spindle while it is being rotated, thereby smoothing the inner wall of the flange and assuring a uniform size and correspondence with the size of the bushing. Owing to the provision of ribs 102 on the operative surface of the pulling ball, this smoothing or ironing effect of the tool is greatly enhanced, and the danger of splitting the metal or mairing it is absolutely avoided.

By means of a screw driver or some other implement, the operator then withdraws the removed pulling head 100 from the stem 107 and again lifts the turret until the bushing is axially withdrawn from the flange just produced therein. The operator may now without rotating the index wheel, axially displace the carriage 6 with the support 16 mounted thereon, through rotation of the hand wheel 10, if it is desired to produce another socket in axial alinement with the first named socket. If the carriage 6 is to be displaced longitudinally, the plunger 93 is first released and will again automatically enter into the selected socket after the displacement of the bed. If, however, the next socket to be produced should be one which is

in circumferential alinement with the first named socket, the operator will not displace the bed longitudinally, but merely rotate the index wheel (after release of its lock) and thereby the mandrel and saxophone body. When the index wheel has been properly positioned, the exact alinement circumferentially is effected by the entry of the locking plunger 33 into a socket 26' of the index wheel, and now the operator may again lower the turret 54 to bring the same bushing into straddling engagement with that part of the saxophone body which is now approximately in alinement with the spindle. If necessary, however, the turret may be selectively rotated until a bushing of a different size is placed into opposition to the socket hole, now in operative position. The turret is then lowered again by means of the hand wheel and the operation is repeated.

When the machine is being operated it is important that the turret 38 be maintained rigidly against vertical movement on the rack and pinion structure 55 and 56, respectively, this being effected by the use of the worm gearing 60 and 61, respectively, which effectually hold the turret in the lowered or operating position.

We claim:

1. In a machine of the character described the combination of a support for an instrument body having holes, means for locking said instrument body on said support against axial and circumferential displacement, the support being provided with recesses in opposition to said holes, said recesses having a diameter larger than the holes, enlarging tools located in said recesses and having the contour of a portion of a sphere, and means insertable into said recesses and radially insertable into the spherical part of the enlarging tools for withdrawing the enlarging tools from the body.

2. In a machine of the character described, the combination of a support for an instrument body provided with holes, the support having recesses in opposition to said holes, enlarging tools located in said recesses, mechanism for withdrawing said enlarging tools from said recesses, and means for adjusting the support relatively to said withdrawing mechanism to selectively bring different enlarging tools into operative relation with said withdrawing element.

3. In a machine of the character described, the combination of a tapering support to which a tapering perforated body of an instrument is removably fitted, an enlarging tool in the interior of the body in opposition to the perforation thereof, mechanism for removing the enlarging tool through the perforation and means for adjusting the instrument body to place that

radial line which passes through the axis of said perforation into truly vertical position.

4. In a machine of the character described, the combination of a mandrel for an instrument body having holes, an enlarging tool in the interior thereof, mechanism for withdrawing the enlarging tool vertically through a hole, a bearing for carrying said mandrel, a support for said bearing and means for adjusting said support to present a plane defined by the axis of the body and the axis of the hole in truly vertical position.
5. In a machine of the character described, a mandrel for a tapering instrument body having holes, a mechanism for enlarging the holes in said instrument body, and means for selectively adjusting the support of the instrument body to bring successively different holes in said body into operative relation to the mechanism.

6. In a machine for producing a socket on an instrument body having a perforation, the combination of an enlarging tool, mechanism for moving said enlarging tool through a perforation of an instrument body, a support for said instrument body and means for adjusting said support relatively to said mechanism in vertical and horizontal planes.

- 20 7. In a machine for producing a socket on an instrument body having a perforation, the combination of an enlarging tool, a mechanism for drawing said enlarging tool through the perforation in the instrument body, a support for the instrument body, means for adjusting said support in the direction of the axis of the body relatively to said mechanism, and means for adjusting support in a direction at right angle to said axis.

- 45 8. In a machine for producing a socket on an instrument body having a perforation, the combination of an enlarging tool, a mechanism for moving said enlarging tool through the wall of the instrument body, a support for said instrument body, means for manually adjusting said support in a horizontal plane in different directions at angles to each other, and means for angularly adjusting said support relatively to said horizontal plane.

- 55 9. In a machine of the character described, the combination of an enlarging tool, a mechanism for moving said enlarging tool transversely through the wall of an instrument body, a bed, a carriage longitudinally slideable on the bed, a support on the carriage, bearings mounted on said support and a mandrel for the instrument body placed on said bearings.

- 60 10. In a machine of the character described, the combination of an enlarging tool, mechanism for moving said enlarging tool transversely through the wall of an instrument body, a bed movably supported

on the machine, a carriage longitudinally adjustable on the bed, a support vertically adjustable on the carriage, bearings movably secured to said support and a mandrel adjustably mounted in said bearings and fixedly supporting the instrument body.

70 11. In a machine of the character described, the combination with a mechanism for producing a socket on an instrument body, of supporting elements for said instrument body adjustable longitudinally and transversely with respect to the mechanism, and means for retaining said supporting elements locked in adjusted position.

75 12. In a machine of the character described, the combination of an enlarging tool, a mechanism for moving the enlarging tool through the walls of an instrument body, including a mandrel to which said instrument body is fixed, a bearing for said mandrel, and means for rotatably adjusting said mandrel in said bearing and for locking the mandrel in adjusted position.

80 13. In a machine of the character described, the combination with an enlarging tool, a mechanism for moving the enlarging tool through the walls of an instrument body, a mandrel on which said instrument body is detachably mounted, bearings rotatably supporting said mandrel, a support for said bearings, one of said bearings being rotatable on said support in a plane parallel to the plane of the support, a carriage longitudinally adjustable in the machine, and means for pivotally supporting said support from said carriage.

85 14. In a machine of the character described, an enlarging tool, mechanism for moving the enlarging tool transversely of the walls of an instrument body, a bushing 105 for guiding said enlarging tool during movement, and means for exactly positioning the bushing in alinement with the axis of the enlarging tool.

90 15. In a machine for producing a flange socket on an instrument body, an enlarging tool located in the interior of the body, a mechanism for moving said enlarging tool through the wall of the body, a bushing 110 adapted to confine the diameter of the flange formed on the instrument body, and means for adjusting said bushing relatively to the body and tool.

115 16. In a mechanism for producing a cylindrical flange on an instrument body, and integral therewith, a bushing adapted to confine the formation of the flange to a certain diameter, and means for adjusting said bushing relatively to the instrument body.

120 17. In a machine for producing a socket on an instrument body having perforations, enlarging tools, mechanism for moving the enlarging tools of different diameters transversely of the walls of the instrument body through said perforations, bushings of vari- 125

- ous diameters and means for adjusting bushings of different diameters to operative relation with respect to corresponding enlarging tools.
18. In a machine for producing sockets on an instrument body, the combination of an enlarging tool, bushings, mechanism for moving a bushing in a direction transversely of the instrument body, a turret having a bottom and a flaring flange, the bushings being mounted in said flange, means for rotating the turret to move a selectively predetermined bushing in opposition to a predetermined part of the instrument body, means for vertically adjusting said turret to bring said bushing into engagement with the predetermined point of the instrument body, and means for moving the enlarging tool through said bushing.
19. In a socket producing machine for an instrument body, flange forming mechanism, a plurality of bushings, a rotary carrier for the same, means for adjusting said carrier to bring a selectively determined bushing into operative relation with respect to the flange forming mechanism and to a predetermined point of the instrument body, locking means for retaining said carrier in said relation, and automatically acting means for releasing the locking means upon movement of said carrier in a predetermined direction.
20. In a socket producing machine for an instrument body, flange forming mechanism, a plurality of bushings, a common carrier for said bushings, said carrier being adjustable to bring a selectively determined bushing into engagement with said body and into operative relation to the flange forming mechanism, a locking element for retaining the carrier in adjusted relation, means for withdrawing the bushing from engagement with said body and means for automatically releasing the locking element upon withdrawal of said bushing.
21. In a socket producing machine for an instrument body, flange forming mechanism, a plurality of bushings of different diameters, a common carrier for said bushings, means for moving a selectively determined bushing into engagement with the body and in operative relation to said mechanism, and for removing it from said position, the carrier being rotatably adjustable, means for locking the carrier in operative position, and mechanism controlled by movement of the carrier for releasing the carrier to rotary adjustment.
22. In a socket producing machine for an instrument body, a flange applying mechanism, including a bushing, a carrier for the same, means for bringing the bushing into engagement with said body, a locking element for the carrier, means for automatically releasing the locking element upon movement of the bushing from said body, and an additional yielding locking device for said carrier independent from the movement of the bushing.
23. In a socket producing machine for an instrument body, a flange applying mechanism comprising a bushing, a rotatable carrier for the same, means for vertically adjusting said carrier on the machine, a locking element for holding the carrier against rotation and automatic means for withdrawing said element from locking position upon vertical adjustment of the carrier in a determined direction.
24. In a socket producing machine for an instrument body a flange applying mechanism, a standard, a bushing, a collar mounted on said standard, a carrier for the bushing vertically adjustable with respect to said standard and rotatably adjustable with respect to the instrument body, means for locking the carrier against rotary adjustment, and means fixed to said collar for effecting release of the last named locking means upon vertical adjustment of the carrier to a predetermined extent.

In witness whereof we have affixed our signatures hereunto this 14th day of October, 1922.

EDWARD J. GULICK.
MORRIS V. HAWKINS.
